UNITED STATES PATENT OFFICE

123,639

DESIGN FOR A RECEPTACLE FOR CIGARETTES, COSMETICS, AND OTHER ARTICLES

Alfred F. Reilly, North Attleboro, Mass.

Application August 26, 1940, Serial No. 94,634

Term of patent 3½ years

To all whom it may concern:

Be it known that I, Alfred F. Reilly, a citizen of the United States, residing at North Attleboro, county of Bristol and State of Massachusetts, have invented a new, original, and ornamental Design for a Receptacle for Cigarettes, Cosmetics, and Other Articles, of which the following is a specification, reference being had to the accompanying drawing, forming a part thereof.

In the accompanying drawing Figure 1 is a top plan view of a receptacle showing my new design; Fig. 2 is a side elevation of the same; Fig. 3 is a front elevation of the same; Fig. 4 is a fragmentary sectional view on the line 4—4 of Fig. 1 on a larger scale; Fig. 5 is a fragmentary

sectional view on the line 5—5 of Fig. 1 on a larger scale; Fig. 6 is a fragmentary sectional view on the line 6—6 of Fig. 1 on a larger scale.

In the article illustrated the side not shown is plain.

The dominant feature of the invention resides in the ornamentation shown in solid lines.

Alternate areas in each row are contrastingly finished as indicated by stippling in Fig. 1.

I claim as my invention:

The ornamental design for a receptacle for cigarettes, cosmetics, and other articles, as shown and described.

ALFRED F. REILLY.
